(57) **CLAIM**

I claim the ornamental design for a window vent canopy, as shown and described.

DESCRIPTION

FIG. 1 is a front elevational view of a window vent canopy of the present invention;

FIG. 2 is a top plan view of the window vent canopy of FIG. 1;

FIG. 3 is a right side elevational view of the window vent canopy of FIG. 1, the other side being a mirror image of this right side elevational view;

FIG. 4 is a top, front, right side perspective view of the window vent canopy of FIG. 1;

FIG. 5 is a top, right side perspective view of the window vent canopy of FIG. 1; and,

FIG. 6 is a top, rear, right side perspective view of the window vent canopy of FIG. 1.
